UNITED STATES PATENT OFFICE.

JOHN H. GILES AND DONALD M. GILES, OF PHILADELPHIA, PENNSYLVANIA.

DYEING MACHINE.

Application filed September 26, 1923. Serial No. 664,950.

In our prior Patent #1,114,464, patented October 20th, 1914, we have described and broadly claimed a novel construction of a dyeing machine wherein the skeins are supported on sticks which are carried by stick supports which revolve within a dye tub, provision being made for the rotation of the sticks at the proper time and also for effecting relative adjustment between the inner and outer yarn stick supports.

Our present invention relates to a machine of this general type but comprehends more particularly novel adjusting mechanism in order to effect the desired adjustment between the outer and inner sticks so that skeins of different lengths can be treated.

It further comprehends a novel and simplified construction of mechanism for simultaneously adjusting the relation between the inner stick supports and the outer stick supports.

Other novel features of construction and advantage will hereinafter more fully appear in the detailed description and the appended claim.

For the purpose of illustrating our invention, we have shown in the accompanying drawings a typical embodiment thereof which is at present preferred by us, since this embodiment will be found in practice to give satisfactory and reliable results. It is, however, to be understood that the various instrumentalities of which our invention consists can be variously arranged and organized and that our invention is not limited to the precise arrangement and organization of these instrumentalities as herein shown and described.

Figure 1 represents a vertical cross sectional view of a dyeing machine, embodying our invention.

Figure 2 represents a section on line 2—2 of Figure 3.

Figure 3 represents a section on line 3—3 of Figure 2.

Figure 4 represents a fragmentary detail of one of the spiders and certain of its adjuncts.

Similar numerals of reference indicate corresponding parts.

Referring to the drawings.

4 designates a dye tub or vat which is adapted to contain the dye liquor which is to be employed. A supporting shaft 5 is journalled in the bearing 6 and this shaft is adapted to be rotated in any desired or

conventional manner. 7 designates spiders fixed to the shaft 5 and having their spokes 8 connected to the outer stick supports 9 which are in the form of rings having apertures 10 of any desired character to receive the sticks, which are the usual yarn sticks, which carry the skeins of yarn which are to be dyed. There are recesses or spaces 11 formed between the outer flanges or clips 13 and the spider spokes.

The spiders are shown as carrying the usual guard rings 14. The yarn sticks are supported by the inner and outer yarn supports in any desired manner and the relative adjustment is effected by the construction and in the manner which will now be explained. The hubs of the spider 7 carry the brackets 15 secured to the spokes 8 in any desired manner and loosely mounted in these brackets is a shaft or rod 16 to which is fixed an operating or adjusting lever 17. This lever 17 is provided with a longitudinally extending slot 18 into which extends a pin or boss 19 carried by the inner stick support 12 at one side of the machine. The inner stick support at the opposite side of the machine is provided with a pin or boss 20 which extends into the slot 21 in an arm 22 which is fixed to the rod 16. The lever 17 near its outer end is provided with a pawl 23 which engages the teeth of a rack 24 formed on the side of the outer stick support 9. The free end of the lever 17 preferably has a polygonal contour in order to adapt it to receive a detachable operating handle shown in dotted lines in Figure 1 at 25. We have represented a yarn skein diagrammatically at 26, see Figure 1.

It will now be understood that the yarn sticks are carried by the inner and outer supports which form a rotatable carrier for them.

If it is desired to tighten or loosen the skeins or, in other words, to vary the distance between the inner and outer stick supports, this can be effected by applying the detachable handle 25 to the lever 17 and thus effect relative rotary adjustment of the inner and outer stick supports.

As the rod or shaft 16 is connected to both of the inner stick supports, it will be apparent that the inner stick supports at each side of the machine are simultaneously adjusted.

In our present construction, we have overcome the necessity of employing springs,

gears or similar metal parts which are liable to be deleteriously affected by the dye liquor.

The general operation of the dyeing machine will be understood by those skilled in this art by reference to our prior patent to which we have hereinbefore referred and a detailed description of such operation is therefore believed to be unnecessary.

In the form illustrated one of the spiders 10 is provided with a gear 27 in order that the carrier may be driven by any desired source of power.

Having thus described our invention what we claim as new and desire to secure by Letters Patent, is:—

In a dyeing machine, the combination with a dye tub of a shaft suitably journalled, spiders including guard rings 14 and clips

carried by said shaft and adapted to revolve through said dye tub, an outer stick support fixed to each spider, an inner stick support rotatably adjustable in said clips, a shaft journalled in said spiders, an arm connected with said shaft and having a pin and slot connection with one of said inner fixed supports, a single lever fixed to said shaft and having a pin and slot connection with the other of said stick supports, a pawl carried by said lever, and a ratchet carried by one of said stick supports to cooperate with said pawl whereby said inner supports can be fixed in the position to which they have been simultaneously adjusted with respect to said outer stick supports.

JOHN H. GILES.
DONALD M. GILES.
